(57) **CLAIM**

The ornamental design for a drill shear attachment, as shown and described.

DESCRIPTION

FIG. 1 is a rear perspective view showing my new design of a drill shear attachment;

FIG. 2 is a rear elevational view;

FIG. 3 is a front elevational view;

FIG. 4 is a left side elevational view;

FIG. 5 is a bottom plan view;

FIG. 6 is a right side elevational view; and,

FIG. 7 is a top plan view.

The broken line drawings of FIG. 1 are for illustrative purposes only to show environment and form no part of the claimed design.
